UNITED STATES PATENT OFFICE.

EDWARD G. KAYSER, OF CHICAGO, ILLINOIS.

BOTTLE-STOPPER FASTENER.

1,192,067.

Specification of Letters Patent. Patented July 25, 1916.

Application filed September 30, 1914. Serial No. 864,269.

To all whom it may concern:

Be it known that I, EDWARD G. KAYSER, a subject of the Emperor of Germany, residing at Chicago, in the county of Cook and 5 State of Illinois, have invented certain new and useful Improvements in Bottle-Stopper Fasteners, of which the following is a specification.

This invention relates to fasteners for bot- 10 tle stoppers, and more particularly stoppers of the cap type in common use.

The invention has for its object to provide a fastener which will securely hold the cap and force it down on the bottle mouth to 15 seal the same, and which can be easily and quickly manipulated to fasten or release the cap.

The invention also has for its object to provide novel and improved means for lock- 20 ing the fastener to prevent accidental disengagement from the cap.

These objects are attained by means of a combination and arrangement of parts to be hereinafter described and claimed, reference 25 being had to the accompanying drawing, in which—

Figure 1 is a side elevation of a fragment of a bottle showing the invention applied thereto; Fig. 2 shows a rear elevation of the 30 device, and Fig. 3 is a view similar to Fig. 1 showing the parts in another position.

Referring specifically to the drawing, 5 denotes a fragment of the bottle to which the invention is applied. The neck of the bottle, near the mouth thereof, is provided with the usual shoulder 6 which serves to retain in place a supporting member for the fastener of the stopper 7 of the bottle, said stopper being an ordinary cap seating on 10 the bottle mouth and having the usual retaining flange. The supporting member is a piece of wire 8 which is bent to partly encircle the bottle neck, beneath the shoulder 6. The ends of the wire are bent into eyes 9 15 which serve as a pivotal support for the fastener, the latter being a piece of wire which is bent to form a cross bar 10 having at one end a loop 11 which passes through the eyes 9. The other end of the cross bar terminates 20 in a downturned hook 12. The fastener is so dimensioned and located that the part 10 may be swung to extend across the top of the cap, and upon being locked in this position, the cap is securely held in place on the bottle 25 mouth.

The following means are provided for

locking the fastener: Adjacent to the ends of the support 8, and diametrically opposite each other, the same is bent to form eyes 13 which pivotally support a bail-shaped lever 60 14. The branches of this bail, adjacent to the pivotal connection of the same with the eyes 13, are bent into eyes 15 to which are connected the respective ends of a locking bail 16 designed to engage the hook 12. The 65 ends of the branches of the locking bail have lateral bends which are slipped into the eyes 13 whereby a pivotal connection between the bail and the lever is had. The cross piece connecting the branches of the bail is en- 70 gageable with the hook 12.

In operation, before the bail 16 can be placed over the hook 12, it is necessary to swing the lever 14 upward until the pivot of the bail is above the pivotal connection of 75 the lever with the support 8. This operation elevates and carries the bail forward a sufficient distance so that it may be swung over the hook 12. Now, to tighten the bail on the hook, the lever is swung downward 80 which exerts a downward pull on the bail and draws it tightly down over the hook. The lever is swung down until the pivots of the bail and the lever are in vertical alignment or slightly past a dead center position, 85 whereupon the bail is locked in holding position, and it cannot be released from the hook until the lever is again swung upward to carry the bail upward and forward off the hook. The downward pull on the bail 90 causes the cross bar to press down on the cap, and the latter is thus tightly clamped on the bottle mouth to seal the same. It will be noted that in the applicant's device the hook 12, and the connecting portion of the 95 bail 14, are on opposite sides of the bottle, and the bail 16 extends diagonally therebetween. It will therefore be seen that the bail 16 tends to draw the bail 14 tightly against the side of the bottle and 100 prevents the same from accidentally slipping up to release the cross bar 10.

By providing the cap fastener hereinbefore described, the bottle may be partly emptied and resealed by replacing the cap 105 and securing the same by the fastening device.

I claim:

The combination with a bottle and a stopper therefor; of a fastener for the stopper 110 comprising a supporting member fastened to the bottle, a stopper holding member piv-

2
oted to said supporting member and adapted to extend across the top of the stopper, a locking bail straddling the bottle, the branches of which bail are pivoted to the 5 support adjacent to the pivot of the stopper holding member and the connecting portion of said bail branches being adapted to engage the side of the bottle when said bail is in locking position, and a bail adapted to engage 10 the free end of the stopper holding member and having its branches pivotally connected to the branches of the locking bail adjacent to the pivot thereof, that part of

the second-mentioned bail which engages the holding member being on one side of the 15 bottle, and the aforesaid connecting portion of the locking bail being on the diagonally opposite side of the bottle the two baills forming an obtuse angle when in locked position.

20

In testimony whereof I affix my signature in presence of two witnesses.

EDWARD G. KAYSER.
